UNITED STATES PATENT OFFICE.

WILLIAM E. NICKERSON, OF CAMBRIDGE, MASSACHUSETTS.

ELECTRIC CONTROLLING DEVICE FOR ELEVATORS.

SPECIFICATION forming part of Letters Patent No. 403,440, dated May 14, 1889.

Application filed March 7, 1889. Serial No. 302,248. (No model.)

To all whom it may concern:

Be it known that I, WILLIAM EMERY NICKERSON, of Cambridge, in the county of Middlesex and State of Massachusetts, have invented certain new and useful Improvements in Electric Controlling Devices for Elevators, of which the following, taken in connection with the accompanying drawings, is a specification.

10 My invention relates to a device located within the elevator-carriage, consisting of moving electric contact-plates operated by the movement of and moving in perfect unison with the elevator-carriage, and a switch electrically connected to the electric controlling devices, said switch being set by the attendant and adapted to remain stationary and keep a circuit closed until one of the moving electric contact-plates has traversed beyond 20 the contact-point of the switch.

I have illustrated my invention by the accompanying drawings, in which—

Figure 1 is a vertical section, showing such parts of an elevator as are required to illustrate the position and general arrangement of my device. Fig. 2 is a horizontal section taken through the switch-box, showing the index-drum in full. Fig. 3 is a front elevation of the switch-box, a part being broken away to 25 show the transmitting-gear. Fig. 4 is a view in perspective showing the more important details. Fig. 5 is a side elevation (enlarged) of the movable contact-block. Fig. 6 is a diagram which illustrates the movement of 30 the contact-plate block in relation to the movement of the carriage and of the index-electrode.

In Fig. 1 I have shown, partly in outline and partly in section, an elevator-well room, 40 A, floors A' A² A³ A⁴, a carriage, B, having a hoisting-rope, B', and electric cable B².

M M' and H H' indicate in a conventional manner two electric devices. One, H H', is intended to operate that part of the controlling mechanism that effects the ascent of the carriage, and the other, M M', is intended to operate that part of the controlling mechanism that effects the descent of the carriage.

D indicates the switch-box, and the dotted 45 circle D' the position of the index-drum.

C and C², Fig. 1, are ropes, one end of each

of which is attached to the index-drum D'. (See Figs. 1, 2, and 3.) One of these ropes—C, for instance—should have a yielding connection, C', to a stationary part. The other may 55 be fixed rigidly, as at C², Fig. 1.

The fixed ropes C and C² are so coiled around the index-drum D', which moves bodily with the carriage B, that when the carriage moves up or down the index-drum must 60 turn in one direction (that of the arrow) when the carriage ascends and in the opposite direction when the carriage descends.

The transmitting device, that connects the index-drum D' with the moving contact-plate 65 block E, (see Figs. 2, 3, and 4,) is shown in Fig. 2, and consists of a shaft, D², having upon it a beveled gear, D³. The beveled gear D³, acting through the gear D⁴, shaft D⁵, and worm D⁶, (see Figs. 2 and 3,) operates the worm-gear 70 D⁷ and through it the shaft D⁸ and contact-plate block E, (in this case a disk.)

I have arranged the transmitting device so that when the elevator-carriage makes its 75 whole passage the block E will make one-fourth of a full rotation in the direction of the arrow, Figs. 3, 4, and 6, when the carriage ascends, and in a direction opposite to the arrow when the carriage descends—that is, the block E will make a part rotation forth and 80 back of ninety degrees as the carriage ascends and descends. As the carriage ascends, the block E will move so that its point marked —4' will move to the point —4 on the index-ring F, Fig. 6, and as the carriage descends 85 the point marked —4' on the block E is taken back to the point marked —1 on the index-ring, whence it started.

The index-electrode K may be moved by the attendant a half-circle—that is, from the 90 point —1 to —4 on the index-ring F.

The contact-plate block E is made in the form of a disk, and has upon it two contact-plates, one of which, H⁴, is connected by the friction-plate H³ and wire H² with the electric device H H'—that is, the one used for ascending—and the other contact-plate, M⁴, is connected by the friction-plate M³ and wire M² with the electric device M M', used for descending.

K, Figs. 2, 3, and 4, is an electrode made in the form of an index-pointer, and for conven-

ience I will call it an "index-electrode." It is connected through the bracket K^2 by a wire, P , to one pole of both of the electric devices.

The index-electrode K is hung by a swivel-
5 joint to the bracket K^2 , Figs. 2, 3, and 4, and has a friction-plate, k , a set-nut, k' , and a hand-wheel, K^3 , by means of which the attendant can set it at any desired point.

The index-electrode K has a contact-point,
10 k^2 , (see Figs. 2 and 4,) which rests upon and makes electric connection with one of the contact-plates H^4 or M^4 , that it is set over. The index-electrode K has also a knife-shaped projection, F^3 , (see Figs. 4 and 5,) which serves
15 to hold it steadily in the position that the attendant has placed it, it being held by one of the notches F^2 , formed in the plates F' on the index-ring F . (See Figs. 4, 5, and 6.) These plates F' are made adjustable—that is, the
20 screws S S , by which they are attached to the index-ring F , pass through slots, as shown in Fig. 5.

The operation of my device is as follows: The carriage being at the bottom—*i. e.*, first
25 floor—the contact-block E will stand (see Figs. 4 and 6) with its division marked $+4'$ opposite the division on the index-ring marked $+4$. Now, if the attendant turns the index-electrode K to the point $+4$ on the index-
30 ring F , it will cause the contact-point k^2 to make an electrical connection with the contact-plate H^4 , and through it and the spring-plate H^3 and wire H^2 to the electric device H H' , completing the circuit through the wire
35 P , bracket K^2 , and index-electrode K , and causing the electric device H H' to operate the device that causes the carriage to ascend. The upward movement of the carriage will continue until the contact-block E has been rotated by the movement of the carriage acting
40 through the ropes C and C^2 and the index-drum D , as has been explained, so far as to carry the contact-plate H^4 out from under the contact-point K^2 . Again, if we suppose the
45 carriage to be at the bottom or first floor, and we wish to go to the second floor, the attendant turns the index-electrode K to the division numbered $+2$ on the index-ring. This will cause the electric connection to be made,
50 as before, and the carriage will start up. Turning the contact-block E in the direction of the arrow, the carriage will continue to ascend until it, acting through the ropes C C^2 , will cause the contact-block E to rotate until the
55 end of the contact-plate H^4 has passed from

under the index-electrode K and broken the circuit, thus causing the carriage to stop. If, instead of the second floor, we had wished to go to the third, then the index-electrode H would have been placed on the division 60 marked $+3$ on the index-ring F . If the carriage is at the top, then the contact-block E will stand with the division $-4'$ on the contact-block opposite the division -4 on the index-ring F , and to cause the carriage to 65 descend, the index-electrode K is moved around to the division -1 on the index-ring. This will cause the contact-point k^2 on the index-electrode K to come in electrical connection with the contact-plate M^4 , and through it and the spring-plate M^3 and wire M^2 put the motor M M' in circuit through the wire P , bracket K^2 , and index-electrode K , thus starting the carriage downward. This motion of the carriage will continue until the 70 carriage has reached the lower floor, at which time the rotation of the contact-block E will have carried the contact-plate M^4 out from under the contact-point k^2 , and the circuit will be broken.

From the above it may be seen that by turning the index-electrode to the proper point on the index-ring the carriage can be directed from one floor to any other, and that the attendant's strength and skill will be but 75 slightly taxed.

I claim—

1. In an electrically-controlled elevator, the combination of contact-plates within the carriage, connected to electric devices and adapted to move in relation to an index the same as the carriage moves in relation to the floors, with an index-electrode adapted to be set by the attendant, substantially as and for the purpose set forth. 95

2. In an electrically-controlled elevator, the combination of the ropes C and C^2 , index-drum D' , a transmitting mechanism, and the contact-plate block E and contact-plates M^4 H^4 with the index F and index-electrode K , all 100 electrically connected, substantially as and for the purpose set forth.

In testimony whereof I have signed my name to this specification, in the presence of two subscribing witnesses, on this 5th day of March, 105 A. D. 1889.

WILLIAM E. NICKERSON.
